UNITED STATES PATENT OFFICE.

SAMUEL K. BAYLEY, OF BOSTON, MASSACHUSETTS.

REFRIGERATOR-CAR.

SPECIFICATION forming part of Letters Patent No. 276,952, dated May 1, 1883.

Application filed March 2, 1883. (No model.)

To all whom it may concern:

Be it known that I, SAMUEL K. BAYLEY, a citizen of the United States, residing at Boston, in the county of Suffolk and State of Massachusetts, have invented certain new and useful Improvements in Refrigerator Cars and Buildings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a longitudinal vertical central section. Fig. 2 is a sectional view on line xx , Fig. 1; Fig. 3, a sectional elevation, showing drip-pan, cooling-pipes, &c.; Fig. 4, an enlarged view, in perspective, of one of the ice-compartments, showing locking-bands; Fig. 5, a sectional view of parts of roof or sunshade; Fig. 6, an end view of rolling curtain as applied to a car. Fig. 7 is a horizontal section of bottom of ice-tank on line xx , Fig. 4; Fig. 8, a detail to show how the tanks are constructed, having bands on the inside. Fig. 9 is a plan view, showing several railroad-cars as in a train, having my improvement; Fig. 10, a side elevation, showing the pump as actuated by the oscillations of the car, a refrigerating-tank, and an extra engine, &c., in the car; Fig. 11, an end elevation, showing one form of the mechanism for pumping by the oscillations of the car; Fig. 12, an end view of a modification of above; Fig. 13, a detail in section, showing the roof of the car centrally inclined or depressed. Fig. 14 is a detail, showing one form of placing the bellows or pump to compress the air to work the pumps and brakes.

My invention consists in so constructing a refrigerator car or building that it can be used either with ice, ice and salt, freezing-mixtures, drippings, compressed air, chemical and power refrigerants, and, finally, the combination of two or more of the forenamed; also, in placing the ice-tanks in the end of such a car, and having a roof which runs downwardly toward the center from the ice-tanks, or placing the tank in the center and making the roof rise upwardly from all sides toward the same, thereby furnishing a hot-air chamber above the goods and af-

fording means for conducting the hot air to such tank or tanks; also, the arrangement of the tanks in the car or room; also, a method of making the lower or bottom ends of the tank detachable and the manner of fastening the same when replaced; also, a drip-pan so constructed that there is no slopping over of its contents, and so arranged that it can be utilized as a receiver or holder of drippings or brine, to be drawn from as needed; also, the construction of an overflow pipe or tube for the drip-pan and its combination with said pan; also, the use of a power to circulate the drip; also, a method of utilizing the drip or brine; also, the construction of a sunshade or supplemental roof; and, finally, the general construction and combination of the several parts of my invention and the method of their use.

It has been found that very few of the many refrigerator-cars carry and preserve their contents successfully. One of the causes of failure is defective circulation of air in the car. I find in flat-roof cars that the hot air hangs a long time next the roof or ceiling, and if the goods are half-way up or near the top of the car the air is apt to condense on them, and so deteriorate their quality and looks. This trouble I overcome by obtaining a circulation of air by making the roof or ceiling slant from or near a central point and run upwardly at an angle toward the top or back of the ice-tanks.

The roof or ceiling of the room or car can have various forms, for it can have a flattened surface before it starts upwardly toward both ends. It also can be flattened, or flat over or partly over the ice-receptacle; or, if the receptacle is placed in the center, it can slope upwardly from all sides toward it. By these forms of construction the hot air rising upwardly from the goods will be taken away almost immediately and conducted rapidly toward the ice-tanks, where it is cooled and passed down and out at or near the bottom, helping to force the hot air upward, consequently making a circulation. This arrangement overcomes one of the greatest drawbacks to the use of refrigerator-cars. It is best to make the deflecting roof or ceiling of some good non-conducting and non-condensing substance. If canvas or similar material

is used, it can be made removable, if desirable. Above the roof of the car I apply what I call a "sunshade," designed to be used more particularly in hot weather. I make it to cover and I place it sufficiently above the roof to leave an air-space between it and the same, and make it detachable. It can be made of wooden slats set apart, of canvas, or any material which will permit of ready application, adjustment, or detachment. For lightness I prefer a properly-prepared canvas, which can be rolled up under the running-board and unrolled or spread when passing through hot districts.

15 A second cause of failure in cars which are run from the extreme north to the far south is the high price of ice at the south and the extra cost above ice of running artificial refrigerants in the north. Artificial refrigerants on cars are very liable to accidents, such as the breaking down of machinery, giving out of material, leakage, and, when the generating machinery is worked by the movement of the car, the setting off on sidings, hot boxes, and 25 waiting for other trains or connections. I overcome these by adapting my car for the use of both the natural and the artificial refrigerants. By "natural refrigerants" I mean ice and its freezing-mixtures, so that when any of the foregoing accidents occur to the artificial refrigerant the natural refrigerants—such as ice—which have been practically kept in *statu quo* by the artificial refrigerants, immediately do their work automatically, and in that way keep the 35 temperature uniform. This to the shipper means everything, for he knows that, within reasonable limits, by no carelessness of the carrier or his employés can his goods become injured by the want of a refrigerant at the right 40 moment. One of my ways of accomplishing this is by placing ice, ice and salt, or other compounds in tanks in either end of the car. Of course these can be put into any desirable position in the car which is considered most 45 convenient and practicable to carry the class of goods offered. The shape of the tanks is immaterial; but I prefer, when I can, to use what is known as the "open" or "exposed" ice system, in order to get the benefit of the oxygen which is freed by the melting of the ice to assist in purifying the atmosphere. The best form I find is a hopper made of metal, having legs or flues depending downward to or near the floor, and as many legs as possible and 55 practicable, as in this way I obtain the largest amount of condensing-surface possible. The closed system can be used—that is, where the tank has no opening into the refrigerating-chamber. Inside or around these tanks or receptacles I place pipes or their equivalent properly connected and attached, through which an artificial refrigerant may be passed, and so arranged as to give off the greatest amount of refrigeration and assist in keeping the natural refrigerant from wastage. I prefer to arrange the pipes, when used inside of an ice-receptacle, in coils at or near its center, and the ice, ice

and salt, or compound I pack around them, leaving the inside of the coils free from ice, &c., so as to form an air space or flue through the ice, &c. Another very convenient way is to place the pipes arranged like steam-heaters diagonally across the inside of the ice receptacle or tank. All these forms can be surrounded by wire-netting or any like substance for the purpose of keeping the ice from falling between the pipes, and so clogging or stopping the air-passages through them from at or near the top to or near the bottom of the tank, and consequently of the car. All the piping of the car should be connected in such a manner as may be necessary for properly conducting the artificial refrigerant through the same. Radiators or coils can be used, both within and outside of the natural-refrigerant tanks, to add to the refrigeration. When it becomes necessary to get into the tanks or flues to cleanse them, or for any other purpose, whether filled with ice or not, in order to overcome the present awkward and impracticable way of slipping one section over the other or tipping it on hinges, I make the bottom or lower end detachable and of two or more pieces hooped or secured together by bands, detachable or not.

The band has its ends extended over the sides, one end with a slot cut into it, the other being tapered, so that it can pass through the slot, and having itself also a slot cut for the reception of a key, which may have a hole punched into its end to allow a ring to be sprung in, in order to hold it from any possibility of its coming out when bent, and so letting the bands apart and contents out. When a round flue is used the bands may be hinged on one or more sides and keyed or locked with a padlock, and in either case the band can be riveted to the out or in side, or remain loose or held up in its place by lugs or projections. When riveted on the inside, projections on the tanks can be so placed as to allow the lower section to depend from it. The corners of the lower or bottom section of the tank, when made of any shape allowing such construction, can be turned in. To stiffen and prevent bulging, as shown in my drawings, where they come together, in order to make a tight joint under the tanks or other receptacles, I put what I call a "drip-pan" to catch the drip from the ice, ice and salt, or compound and condensed moisture, when it falls by liquefaction caused by any means. This pan collects and holds all this waste in such a manner as to prevent its slopping over from the knocking about or oscillations of the car when on the road, and allows any excess of drip to run off. It is arranged with a roof slanting downward toward the center from all or two sides, having an opening at or near its center to allow the drippings to run into the pan. The edges at this opening are turned inward almost or at right angles with the roof to prevent the slush coming upon the roof again. Under one side of this roof is placed the overflow-pipe, which is arranged to be detachable at or below the bottom of the pan.

The pan can have its bottom flat or sloped, similar to the roof, with its center where the overflow-pipe is placed. This overflow-pipe can be made in two or more parts and secured together, or simply slipped together, or with joints and gaskets. These are a few of the many forms of making it. The bottom should have a suitable trap, which will prevent the inlet of air and dirt and allow the free overflow of the drip and waste. Hand-holes can be placed at any convenient part of the pan, with proper covers, and the top of the pan can be made to lift in any manner. In the drip-pan there is arranged a pipe with a flexible end, having the mouth wired, and having floats to keep it above the sediment. The other end is attached to or connected with a power which draws, lifts, or drives the drip. This pan which I have arranged gives better results than any heretofore tried, as it does away with the possibility of sloppage or overflow into the car, and at the same time retains what drip is necessary to supply the power and carrying off all excess of wastage.

I find that the drippings or wastage of ice, ice and salt, or compounds is about the same temperature as the refrigerant itself, and in order to utilize this I circulate it through the series of pipes or other conductors which I put in the car and tanks, and have heretofore described for artificial refrigerants, to obtain what latent cold it may contain, and at the same time to assist in keeping the refrigerant from wastage. This drip can be used, conjointly or alternately, with an artificial refrigerant through the same conductors, or an extra set can be provided for it. By utilizing the drip in this manner a great saving is obtained, as it assists very materially in reducing the meltage of the natural refrigerant, and consequently gives a certain amount of security to the even temperature, which is of so essential importance in carrying refrigerator goods long distances. It also allows of less weight of ice being put into the car to carry the required distance, as the wastage is so much less. I agitate or circulate this drip through pipes or their equivalents in the car in any suitable manner, such as by suction, lifting, or force. I obtain my power for doing these by attachments to the trucks or to an extra pair of wheels on the truck or car, which run loose and free, to which the mechanism is attached, or from windmills or wind-power, oscillations of the car or other cars, power furnished or transmitted by the locomotive or from other cars, or by collected or stored power, or by power attached to the car. This drip can be taken from one or more cars and used as a refrigerant for others. It can be collected to one center, and then refrigeration added or not, or itself help to add, and redistributed, or it can be collected from one or more cars and distributed to one or more to assist in their refrigeration. These are a few of the many ways of utilizing and arranging the agitating of the drip.

When a number of the cars are used in a

train, to obviate the loading down of the cars with the machinery for the artificial refrigerant and carrying it about when not wanted, I prefer placing it all or nearly all on one car, which can be readily attached to the train, and then, in case of accident to the power or refrigerant, another can take its place without much delay. The power for same can come from any of before-mentioned ways of obtaining it. The machinery, in some forms for making artificial refrigerants, can be readily placed on the engine.

All the attachments and machinery where the refrigerants could come in contact to heat should be covered, when outside of the insulated chamber, with a good non conductor of heat and cold. All piping and couplings between cars and locomotive should be flexible and covered with a good flexible non-conductor, such as hair, felt, and paper, and canvas or rubber.

My method of using the drip and power refrigerants with natural refrigerant does not in any way interfere with the keeping of the temperature, when thus withdrawn from the car, at or near its former level, if from any accident they cease to work.

The receptacle for ice, ice and salt, or compound are made preferably of some good conductor of heat and cold, and also a good condenser of moisture, such as galvanized iron or metal prepared to prevent decomposition from the action of salt and ice or compound. The tank or receptacle for the natural refrigerant can have the air-flues ^c placed within it from its top to its bottom, and can be surrounded on its outside by the piping or conductors of the artificial refrigerant; or, as I have previously explained, the air-flue itself can be made of a coil of piping or other suitable conductor, which can be used for the passage of the artificial refrigerant. So many combinations are possible without special invention, but embodying the use of my new system of combining in cars the use of both natural and artificial refrigerants for controlling the temperature of the same—such as the placing of the piping, the tanks, &c.—that I will not here further specially enumerate them. With this combination of both natural and artificial refrigerants in cars the degree of temperature is thoroughly under control and can be kept above or carried below the freezing-point, as may be desired. If below the freezing-point, I am aware that moisture may condense on the piping. It is, however, of too flaky or light a character to have any refrigerating value, and does not of itself bear upon my system of using tanks filled with ice, or ice and salt, or compound. It should, however, be understood, as bearing on my invention, that the closed system of tanks can be used, having the pipes for artificial refrigerants passing through or around them; that such tanks can be constructed with air-flues or their equivalents within and passing through them from top to bottom for the purpose of chilling the air as it

settles down through them, and that said tanks can be filled with water, which shall be made into ice by the action of the artificial refrigerant.

5 The inside roof or ceiling can have other forms when used with both the natural and artificial refrigerants—such as sloping downwardly on both sides—when the receptacles are placed longitudinally through the center 7c
10 of the car or room; also, when the receptacles are placed in the opposite diagonal corners or sides of the car or room the ceiling or roof slopes downwardly from each.

Having above stated the general object and 15 range of my invention and how it is carried out, I will now proceed to explain its operation by reference to the accompanying drawings, in which—

A denotes the car; B, the ice-tanks, (now 20 shown as placed at each end of the car.) The ice-tanks may be placed near the middle of the car, if desired. The tanks may be of any suitable shape or size, and may have a flaring upper part, as now shown at the left-hand side 25 of Fig. 1. The pipes or hollow plates C in these tanks are used to conduct the refrigerant and the drip, and may be any desired shape, size, &c., and pass through said tank from top to bottom, or part way from top to 30 bottom. Usually there are two of these in each tank. There may be any desired number of these tanks placed side by side, so as to extend across the car. The pipes or hollow plates C are suitably connected with each 35 other at their upper and lower ends, so that a continuous circulation is had through the pipes in each and all the tanks. Ice or any cooling compound is placed in each tank about the said pipes or plates C.

40 I have found very desirable results obtained by covering the pipes or plates C with wire-netting, as shown at c''. This prevents small pieces of ice clogging up the spaces between the pipes, and insures a free circulation of air 45 about therein. At one side one end, c, of the pipe C connects with a pump, D, communicating in any desired way with the drip-pan E, which is in the bottom of the car, preferably. Thus the contents of the pan E can be forced 50 into one of the pipes or plates C, and thence, being circulated through the system, will be returned to the pan at the opposite side through the open end c' of the pipe or plate, or plate C on the opposite from where the circulation began. The drip-pan E holds the wastage of the 55 ice, &c., from the tanks B, which will flow down through the lower open ends of each upon the inclined upper sides, a top, e, of the pan; and thence through the pipe e' into it. 60 Conveniently situated at one side of the pipe e' is overflow-pipe F. This overflow-pipe is made in two parts, f f'', and screwed or joined together at or near the bottom of the drip-pan. The advantage of this construction is that the 65 overflow pipe can at any time be readily taken apart when it is desired to clean out the pan E.

The lower end of this pipe can be sealed by means of the bucket f''. The bottom of the pan E is inclined and about parallel with the top e, as clearly shown in Fig. 3. This construction insures an easy movement of its contents when the car is in motion and preventing slopping. The edges of pipe e', projecting into the pan, will also prevent any escape of the drip in this direction. 75

In the sides of the pan E are any suitable number of hand-holes e'', which are capped in any desired way. The pump-connection with the pan E has at its end a flexible pipe, d, and float, d', so that it can rise or fall automatically, 80 as required by the height of the contents of the pan, and suitable cut-off, d'', can be used in the pipe d. The pump is driven by power derived from the truck or any running part of the train, by windmill, or in any desired way or 85 manner. A mode of connection with the axle is now shown at d'', which indicates one of these many ways.

The lower ends, b, of the tanks B are detachable, and are formed for this purpose in 9c two or more parts, which are secured together and to the end of B by means of the metallic band b', which is locked by keys and slots, as shown in Fig. 4.

Fig. 8 shows in detail the construction of the 95 detachable part of the tank. The band b' is riveted to the inside of the detachable portion, and when this detachable portion is placed on the fixed part B it is suspended thereon by means of said band, b', which rests on the offset b³ on the fixed part.

The ceiling A' of the car is so deflected from the tanks B that its highest point is near the said tanks. Thus when the hot air rises it flows toward the ice-tanks into the space above 105 the goods carried in the car, and thence flowing through the ice-tanks circulates in the course indicated by the arrows, till, having been suitably cooled, it is returned again at the lower part of the car. The goods in the car are 110 hung up, as on rods or slats a, or disposed or packed in any desired way. The car-door may be centrally located, as shown at A'', or otherwise. Of course, if the tanks are placed centrally, the roof will slope in the opposite direction from what is now shown. The essential condition of the case is that the construction shall provide the hot-air upper chamber above spoken of. 115

Above the roof of the car I have a supplemental or detachable roof, G, Fig. 5, which, for a convenient name, I call a "sunshade." This is made in two or more parts detachably secured on each side to the running-board a' of the car-roof. They may be made of canvas 125 and light strips of wood connected together by bands. They may be rigid or flexible. Thus they can be removed or rolled up when desired. (See Fig. 6.)

I have above stated that the drip is carried 130 through the pipes; but, if desired, I may so construct and arrange the parts that the drip

may be carried through a part of said pipes and a refrigerant through a part, or a refrigerant through all.

In some instances it may be well to allow the drip flowing, as above described, through the pipes C to escape directly to the ground out of the end c', instead of into the drip-pan.

While I have shown a very desirable form of constructing the tanks, yet in the details of carrying out my invention I may make many slight changes without departing from the essential idea stated. I may use close tanks, in which the ice, &c., are confined, instead of open tanks.

5 In Fig. 9 I have illustrated how my invention may be applied in use in several or an entire train of cars. In this Fig. 9, in car No. 1 the pump D, actuated by the motion or movement of the car, drives the drip through the pipe e' into car No. 2, and through it by the same pipe, e', in which it is jointed at the pump D by the drip from car No. 2, and the combined drip is thrown into the tank I of the car No. 3, whence it is pumped back into car No. 25 2 through pipe e'' and through the coils C of the cars No. 2 and No. 1. When the drip is in tank I it can be treated with any artificial refrigerant. If two coils, C C', are used, the second will be devoted to the artificial refrigerant. In this train I may have a car, as No. 30 4, without any refrigerant, and into this car pump directly from car No. 3, by suitable pipe-connections, either the drip or the drip and refrigerant, as may desired.

35 In Figs. 9, 10, and 11 are shown two ways how the pump or its equivalent may be actuated by the oscillations of the car by means of rod or cords d⁴ and levers or pulleys d⁵, suitably jointed or connected at one end to the body or sill of the car, and pivoted to the truck, or spring-plank of the truck, and at the other to the piston of the pump. When the pumping mechanism is not used for refrigerating purposes it can be used for compressing air for the brakes and power purposes, as shown in Figs. 10 and 14.

In Fig. 13 I have shown a roof depressed at the center and sloping up toward each end of the car. A car made in this form will give 50 substantially the same result as one in which a supplemental inclined ceiling is used, as in Fig. 1. In Fig. 13 the running-board a³ is held up by suitable supports from the roof.

In Fig. 14 I have placed the bellows on the 55 end piece of truck-frame and attached it to car-body to take the vibratory movement of the truck and utilize it to compress air into a cylinder to be drawn from to work the pump and air-brakes.

60 Having now described my invention, what I desire to claim is—

1. In a combination of two or more refrigerator-cars, the use of the natural-refrigerant drip of one or more of them to refrigerate the others with, substantially as and for the purpose described.

2. A refrigerator-car having the roof or ceiling depressed at the center of the car and sloping upwardly toward each end, substantially as shown.

3. In a refrigerator-car, a warm-air chamber in the upper part, formed between the top of the car and a supplemental ceiling which is depressed in the center of the car and slopes upwardly to near the top of the refrigerating-tank at each end of the car, whereby no dead or non-circulating air is permitted in the car below said supplemental ceiling, substantially as shown and described.

4. A refrigerator car or room having detachable slanting inside ceiling, as and for the purpose described.

5. A detachable supplemental sunshade-roof for cars.

6. A detachable supplemental sunshade-roof for cars, which can be rolled up and retained on the car, substantially as and for the purpose described.

7. In a refrigerating-tank, vertical air-flues formed of pipes with or without wire-netting, 90 to assist in excluding ice from such flues, the pipes being adapted for the circulation of an artificial refrigerant within them, whereby artificial and natural refrigerants may be used conjointly, or either one separately, substantially as shown and described.

8. An ice-receptacle for a refrigerator car or room, having its lower part detachable into two or more parts, substantially as described.

9. An ice-receptacle for refrigerator car or room, having its lower part detachable into two or more parts, and these parts held together by one or more bands arranged substantially as and for the purpose described.

10. An ice-receptacle having the lower end detachable, and secured on by bands riveted to the inside of the detachable part, said detachable part being held up from the floor by projections on the receptacle for its upper band to rest upon, substantially as and for the purpose described.

11. A refrigerator-car adapted to use a natural refrigerant and its drip with an artificial refrigerant, substantially as shown and described.

12. A refrigerator-car having a pump or pumps operated by the oscillatory or vibratory motion of car-body and truck, for circulating drip-water or other refrigerant through the cars, substantially as set forth.

13. A drip-pan for a refrigerator-car having a roof and bottom both slanting in the same direction, in combination with a floating nozzle mounted upon a flexible outlet-pipe, whereby the sediment is retained within the drip-pan, substantially as and for the purpose set forth.

14. The combination, in a refrigerator car or room, of a roof slanting downwardly from the receptacle for a natural and artificial refrigerant, and the receptacle having air-passages through it.

15. In the refrigerator-tanks of a car, coils of pipe forming open-air flues through the coils within the ice, in combination with pumps having suitable connections and adaptation for forcing a circulation of either drip-water or artificial refrigerants through the pipes forming such coils, substantially as set forth.

16. The combination, in a car, of a receptacle or tanks for the use of both an artificial and a natural refrigerant, and a roof sloping downwardly from the top of the tanks toward the sides.

17. A car or room having a receptacle or tanks for the use of both an artificial and a natural refrigerant, with a vertically-inclined air-flue passing within and through the same from its top to its bottom.

18. A refrigerator-car having a closed tank

for holding ice, ice and salt, or compound, and pipes for artificial refrigerant, said tanks having vertical air-flues through the same.

19. A refrigerator-car having a supplemental detachable inside sloping ceiling.

20. A refrigerator car or building having ice receptacle or tanks with tubular coils or other forms of pipe suitably arranged within or around them, and connected together for artificial or drip refrigerants, and vertical air-flues passing through them.

In testimony whereof I affix my signature in presence of two witnesses.
